(57) **CLAIM**

The ornamental design for a diffuser assembly for automobile or replica thereof, as shown and described.

DESCRIPTION

FIG. 1 is a front, right isometric view of a diffuser assembly for automobile or replica thereof;

FIG. 2 is a rear, right isometric view of FIG. 1;

FIG. 3 is a right side elevation view of FIG. 1;

FIG. 4 is a left side elevation view of FIG. 1;

FIG. 5 is a rear elevation view of FIG. 1; and,

FIG. 6 is a top plan view of FIG. 1.

The evenly spaced broken lines in the drawings illustrate portions of the diffuser assembly for automobile or replica thereof that form no part of the claimed design.
